UNITED STATES PATENT OFFICE.

FRED C. PAATSCH, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

HYDRAULIC MACHINE.

Application filed November 17, 1922. Serial No. 601,456.

To all whom it may concern:

Be it known that FRED C. PAATSCH, a citizen of the United States, residing at Milwaukee, in the county of Milwaukee and

5 State of Wisconsin, has invented a certain new and useful Hydraulic Machine; of which the following is a specification.

This invention relates in general to improvements in the construction of hydraulic 10 machines, and relates more specifically to an improved frame and housing structure for impulse water wheels and the like.

An object of the invention is to provide an improved frame structure for hydraulic 15 machines, which is simple, compact and rigid in construction. Another object of the invention is to provide simple and efficient means for housing hydraulic machines and the like.

20 It has heretofore been customary in the construction of hydraulic machines such as impulse water wheels, to provide each machine with a sheet metal readily removable cover supported by a special cast metal 25 frame. These cast metal frame structures of the prior art were very costly and were difficult to transport and to install.

The present invention contemplates provision of a frame structure especially applicable to impulse water wheels, which is formed entirely of structural steel of standard cross-section. Such a frame structure besides being much cheaper to construct, may be more readily transported 35 and installed and produces a more rigid and neat assembled frame structure. The structural steel bars may be cut into suitable lengths and fitted in the shop, after which the frame may be disassembled and shipped 40 in relatively compact form to the destination, where the frame may be conveniently finally assembled. The weight of such a frame is also considerably less than that of the prior cast metal frame structures without sacrificing strength in the completed 45 structure. These and other advantages of the present invention will be apparent in the course of the following description.

A clear conception of an embodiment of 50 the invention and of the manner of constructing devices in accordance therewith may be had by referring to the drawing ac-

companying and forming part of this specification in which like reference characters designate the same or similar parts in the 55 various views.

Fig. 1 is a vertical section through an impulse water wheel installation embodying a frame constructed of structural steel bars having standard cross-section.

60 Fig. 2 is a fragmentary transverse vertical section through the nozzle pit of an improved impulse water wheel installation.

Fig. 3 is an enlarged fragmentary transverse vertical section through the frame 65 structure of an installation such as illustrated in Fig. 1.

Fig. 4 is an enlarged fragmentary transverse vertical section through a modified impulse water wheel frame structure.

70 The hydraulic power installation illustrated in Fig. 1 comprises in general a rotor 2 mounted upon a horizontal main shaft 3 and having a series of peripheral buckets adapted to receive a jet of water delivered 75 from the nozzle 4 in line with an adjustable control needle 14. The upper portion of the rotor 2 is inclosed by a removable sheet metal cover 5 having an angle bar 6 secured thereto by any suitable method such as by 80 riveting or welding. The angle bar 6 has a flange formed for coaction with the upper flange surface of a structural steel channel bar 7 as indicated in Figs. 1 and 3, the angle iron 6 and channel bar 7 being detachably 85 connected by means of a series of bolts 15 which are readily accessible from the casting exterior. The lower flange of the channel bar 7 coacts with a liner plate 10 and is embedded in the concrete foundation 9 as indicated. A drip catch channel bar 8 which is also preferably formed of structural steel of standard cross-section, extends longitudinally of the channel bar 7 and is preferably secured 90 thereto by means of rivets or by welding. This drip catch channel bar 8 may be located at any convenient place relatively to the bar 7, so that drippings from the cover 5 and other elements will collect in the channel bar 8 from which they may be conducted 95 in any suitable manner. The channel bars 7, 8 are preferably formed in sections of convenient length for transportation, and

the adjacent ends of the sections may be firmly connected in any desired manner.

The end of the nozzle pit of the turbine is also provided with a standard channel bar

- 5 13 bent into U-shape as indicated in Fig. 2, the bar 13 having both of its flanges embedded in the concrete of the foundation 9. The nozzle 4 adjacent to the bar 13 is encircled by a standard angle bar 11 one 10 flange of which engages the periphery of the nozzle 4 and the other flange of which coacts with a sealing plate 12. The sealing plate 12 is preferably formed of sheet metal and engages an end of the channel bar 13 so 15 as to completely segregate the interior of the wheel casing from the nozzle pit.

In the modified constructions of the frame illustrated in Fig. 4, one of the elements, namely the angle bar 6, is dispensed with 20 and the drip channel bar 26 which is secured directly to the cover 25 serves as an intermediate support between the cover 25 and the frame channel bar 27. The drip catch channel 26 is detachably connected to 25 the upper flange of the channel bar 27 by means of bolts 30 and the lower flange of the channel bar 27 coacts with a lining plate 28. The concrete foundation 29 engages the channel bar 27 and the lining 28, 30 the latter elements preferably being anchored to the adjacent concrete in any convenient manner. The channel bars 26, 27 are preferably formed in sections of convenient length for transportation, the adjoining 35 ends of the sections being provided with suitable connecting means.

It will be obvious that the use of structural steel bars of standard commercial cross-section, reduces the cost of construction to a 40 minimum. The strength of the assembled structure may be made equivalent to that of a much heavier cast metal frame such as previously used. By making the structure sectional, the various elements may be 45 shipped in relatively compact form thereby greatly facilitating transportation. The assembled structure presents an extremely neat and mechanical appearance and is readily assembled and dismantled.

- 50 It should be understood that it is not desired to limit the invention to the exact details of construction herein shown and described, for various modifications within the scope of the claims may occur to persons skilled in the art.

It is claimed and desired to secure by Letters Patent:

1. In combination, a rotor, a cover for said rotor, a structural steel bar of standard cross-section forming a support for said cover, said cover being removable from said support, and a drip catch coacting with an upper portion of said bar.
2. In combination, a rotor, a cover for 65 said rotor, a structural steel bar of standard

channel cross-section forming a support for said cover, means detachably connecting said cover and said bar, and a drip catch secured to an upper portion of said bar.

3. In combination, a rotor, a cover for 70 said rotor, a structural steel bar of standard cross-section forming a support for said cover, and a drip catch for said cover associated with an upper portion of said bar and completely surrounding said cover. 75

4. In combination, a rotor, a cover for said rotor, a structural steel bar of standard channel cross-section forming a support for said cover, and a drip catch for said cover associated with said bar, said drip catch 80 comprising a second structural steel bar of standard channel cross-section.

5. In combination, a rotor, a cover for said rotor, a concrete foundation, a structural steel bar of standard channel cross- 85 section embedded in said concrete and forming a support for said cover, and a drip catch for said cover secured to said bar.

6. In combination, a rotor, a cover for said rotor, a concrete wall forming a pit 90 for said rotor, a structural steel bar of standard channel cross-section embedded in said concrete and forming a support for said cover, and a drip catch for said cover secured to said bar, said drip catch comprising a second structural steel bar of 95 standard channel cross-section.

7. In combination, a rotor, a cover for said rotor, a concrete wall forming a pit for 100 said rotor, a structural steel bar of standard channel cross-section embedded in said concrete and forming a support for said cover, a second pit extending laterally from said 105 rotor pit, a structural steel bar surrounding the mouth of said second pit, and a sheet metal plate between said pits and coacting with said latter structural steel bar.

8. In combination, a rotor, a cover for said rotor, a structural steel bar of standard channel cross-section forming a support for 110 said cover, and a drip catch associated with said bar and completely surrounding said cover, said drip catch comprising a second structural steel bar secured to an upper portion of said cover supporting bar. 115

9. In combination, a rotor, a cover for said rotor, a concrete foundation, a structural steel bar of standard channel cross-section fixedly held by the concrete of said foundation and forming a support for said cover, and a drip catch secured to said bar and completely surrounding said cover. 120

10. In combination, a rotor, a cover for said rotor, a concrete foundation, a structural steel bar of standard channel cross-section fixedly held by the concrete of said foundation and forming a support for said cover, and a drip catch secured to an upper portion of said bar and surrounding said cover. 125 130

11. In combination, a rotor, a cover for said rotor, means forming a pit for said rotor, a structural steel bar of standard channel cross-section surrounding said pit and forming a support for said cover, means forming a second pit extending laterally from said rotor pit, a structural steel bar surrounding the mouth of said second pit, and dividing means between said pits and coacting with said latter structural steel bar. ¹⁰
